UNITED STATES PATENT OFFICE.

CLYDE S. WRIGHT, OF TOLEDO, OHIO, ASSIGNOR TO THE NATIONAL SUPPLY COMPANY, OF TOLEDO, OHIO, A CORPORATION OF OHIO.

PULLING-MACHINE.

1,324,221.

Specification of Letters Patent.

Patented Dec. 9, 1919.

Application filed December 7, 1918. Serial No. 265,695.

To all whom it may concern:

Be it known that I, CLYDE S. WRIGHT, a citizen of the United States, residing at Toledo, in the county of Lucas and State of Ohio, have invented new and useful Improvements in Pulling-Machines, of which the following is a specification.

My invention relates particularly to machines for the pulling of tubing, rods, and 10 the like from oil wells, but it may be employed for pulling or lifting various objects in other relations.

It is the principal object of this invention to provide a mechanism, incorporated in 15 the pulling machine, by which the latter may be raised from a substantially horizontal position on a truck to a substantially vertical position with the expenditure of comparatively small force. Another object 20 is to mount the machine so low on the truck as to make a safe and stable load during its transportation. Another object is to provide means for leaving the truck on the ground during the hoisting of the machine, 25 so that the truck may be repaired, if required, without loss of time, while the pulling machine is in use. The truck may be used also as a brace for steadyng the base of the mast after its erection.

30 Referring to the accompanying drawings, Figure 1 is a side elevation of my pulling machine in position on its truck for transportation; Fig. 2, a side elevation showing the mast partly elevated; Fig. 3, a side elevation showing the mast fully elevated; Fig. 35 4 a top plan view of Fig. 1; Fig. 5, a broken sectional view showing the truck and the lower end of gin-pole frame, the truck wheels being omitted and parts being in section; and Fig. 6, a side view of Fig. 5.

On the drawings, 1 represents a skeleton mast supported on the cross-piece 2 of the gin-pole frame, having the upright side posts 3, one on each side of the mast. Each 45 end of the cross-piece has a downwardly extending projection 4 with an open-ended recess 5 in which the axle 6 of the truck rests. 7 represents the truck wheels on the ends of the axle. The cross-piece 2 is placed 50 approximately beneath the center of gravity of the mast and the apparatus which it carries, and is connected at each end to the bracket 8 on the mast by a rod or link 9. Each end of the axle is connected by a link

10 to the said bracket, which is secured to 55 the heavier end of the mast, that is, the end which supports the winding drum 11.

The side posts 3 of the gin-pole frame have in line with themselves, the supplementary masts or gin-poles 12 which are 60 substantially vertical when the mast 1 is horizontal, or on the truck. The gin-poles 12 pass loosely through the clips or guides 13 on the sides of the mast 1. A sheave 14 is mounted on the top of each gin-pole 12, 65 and a second sheave 15 is carried by the bracket 16 on the upper corner-members of the mast 1, the sheaves 14 and 15 being in line with the top of the mast 1. Hoisting lines 18 extend from the points 17 beneath 70 and back of the gin-poles 12, over the sheaves 14, thence under the sheaves 15, and over the sheaves 19, one being connected to each side of the top of the mast 1. The lines 18 are preferably a single rope or 75 cable, which is looped on the sheave-block 20, which carries the line 21 for hoisting the mast 1.

The drum 11 may be operated by cranks 22 on the ends of the drum-shaft 23, or by any other suitable power. A hoisting line 24 extends from the drum over the pulley 25 on the top of the mast 1, and has one end connected to apparatus such as 26 to be pulled from the well 27. The other end 85 of the line 24 passes under the drum 11 and is connected to a suitable source of power, or it may be connected to the drum and operated by the handles 22.

The pulling machine mounted on the 90 truck as shown on Fig. 1 is drawn to the vicinity of a well, as 27, from which tubing, rods, and the like are to be pulled. An abutment composed of one or more stakes 28, for example, is made near the well. The 95 machine is placed in line with the well and the abutment, and tilted with the drum end down and in engagement with the abutment and the ground or a temporary floor 29 on the ground. The line 21 is then operated 100 to put strain on the lines 18, the first effect of which is to raise the mast 1 up on the gin-poles 12, the foot of the mast moving on the abutment and floor as on a pivot. This first effect brings the mast from the 105 position shown on Fig. 1 to that shown on Fig. 2, where the mast 1 is drawn up to the top of the gin-poles 12. The second

effect of the operation of the line 21 is to raise the mast 1 together with the gin-pole frame, the links 9 and the gin-poles 12 to the vertical position shown on Fig. 3, the 5 mast 1 and the gin-poles 12 being held together by the lines 18, the mast 12, and the bracket 15. When the mast 1 is raised to its upright position (Fig. 3), it is suitably anchored, the lines 18 and 21 forming one 10 anchor line. 30 represents another anchor line.

It is to be noted that the truck remains on the ground when the gin-poles are raised. The links 10 may be disconnected from it, 15 if desired, in order that the truck may be used for some other purpose during the pulling operations. The truck or the links 10 may be used to brace the mast 1.

I claim—

20 1. In a pulling machine, a main horizontal mast, an upright mast having its upper end above the main mast and between the ends thereof, a single hoisting line, and sheaves carried by the masts and 25 threaded by the line, whereby, when the base of the main mast acts as a pivot, the travel of the line first raises the first mast on the second, and, after the main mast reaches its limit of travel on the second mast, the continued travel of the line raises 30 the main mast to an upright position.

2. In a pulling machine, a main horizontal mast, an upright mast having its upper end above the main mast and between 35 the ends thereof, a single hoisting line, and sheaves carried by the masts and threaded by the line, one of the sheaves being near the top of the main mast, whereby, when the base of the main mast acts as a pivot, 40 the travel of the line first raises the first mast on the second, and, after the main mast reaches its limit of travel on the second mast, the continued travel of the line

pulling on the said main-mast pulley raises the main mast to an upright position. 45

3. In a portable pulling machine, a truck comprising an axle and wheels thereon, a main horizontal mast supported by the truck, a supplementary upright mast supported by the truck between the ends of the 50 main mast and extending above the main mast, sheaves carried by the masts, one of said sheaves being on the second mast above the main mast and another sheave being toward the top of the main mast and beyond the second mast, and another sheave being on the main mast near the second mast, and a hoisting line passing over the first sheave, beneath the third sheave and around the second sheave, whereby the line 60 first causes the main mast to travel up the second mast while the base of the main mast serves as a pivot and, when the main mast reaches the limit of travel on the second mast, the line, pulling on the second sheave, 65 then raises the main mast on said pivot to an upright position.

4. In a portable pulling machine, a truck, a frame resting thereon and comprising upright posts and a cross-piece connecting 70 them, a main horizontal mast supported by the cross-piece, a pair of upright masts having their lower ends carried by the posts and their upper ends extending above the main mast and at opposite sides thereof, a 75 sheave at the top of each mast, sheaves on the main mast near the upright masts, and a pair of hoist lines connected at one end to a fixed support and each threaded over a sheave at the top of an upright mast, beneath the sheave on the main mast and adjacent to the first sheave, and around the sheave at the top of the main mast. 80

Signed at Toledo, Ohio, this 2nd day of December, 1918.

CLYDE S. WRIGHT.
